KING C. GILLETTE, OF BROOKLINE, MASSACHUSETTS.

SAFETY-RAZOR.

1,111,721.

Specification of Letters Patent. Patented Sept. 22, 1914.

Application filed March 6, 1905. Serial No. 248,505.

To all whom it may concern:

Be it known that I, KING C. GILLETTE, a citizen of the United States, and resident of Brookline, in the county of Norfolk and State of Massachusetts, have invented new and useful Improvements in Safety-Razors, of which the following is a specification.

My invention is intended to provide a simple, practical and inexpensive safety razor, and the nature and advantages of my improvements will clearly appear from the ensuing description.

In the accompanying drawings. Figure 1 is a plan view of the head or blade end of one form of my razor. Fig. 2 is a side elevation thereof, partly in section, looking in the direction of the length of the blade, and Fig. 3 is a side elevation of the same parts as viewed from the right in Fig. 2. Fig. 4 is a central longitudinal section showing a modified construction, and Fig. 5 is a side elevation of the handle portion of another modified construction. Figs. 6 and 7 show still another modification, viewed from the same directions as in Figs. 2 and 3 respectively. Fig. 8 is a transverse sectional view showing a modified construction of the head of the razor.

The blade 2 of my razor may be of any usual or desired construction, but is preferably made of sheet steel of uniform thickness and sharpened at both of its longitudinal edges to provide two opposite cutting edges 3-3. The handle member or holder comprises two similar parts or halves 4-4, which are connected at a distance from the blade-engaging devices of the razor in such manner as to swing toward and away from each other. Said holder is preferably stamped from a single piece of sheet metal cut to form the two halves of a head portion having substantially the length of the razor blade, and to have a less width between said head portion, so that when the blank is bent midway between its ends to bring the two halves of the head into opposed relation to each other the narrower portions of the blank will form the handle proper. The configuration given to the holder in its complete form may be as represented in Figs. 2 and 3, in which the two halves of the head are shown as bent or bowed outwardly or

away from each other to provide a space between them of sufficient width to receive the blade 2, the portions which form the handle being slightly curved transversely in order to give the handle a rounded exterior surface.

At the blade end of the razor each of the two halves of the holder is provided with devices for securing and positioning the blade, which devices preferably consist of lugs 5 formed integral with the holder and bent inward in such manner as to overlie and engage the outer surface of the blade when placed in position and hold it in contact with suitable bearing surfaces located on the opposite or inner side of the blade, such for example as are provided by the guard teeth hereinafter described. In the constructions illustrated in the drawings said lugs 5 are located at points corresponding to the normal position of the corners of the blade 2 and are bent diagonally inward, said corners being rounded as at 6 to engage said lugs. This rounding of the corners of the blade preferably extends far enough to include a portion of each end of each cutting edge, thus preventing the blade from having any sharp corners which might be liable to injure the skin of the user.

7-7 represent guard teeth of the usual shape, extending in series between the lugs 5 on the corresponding side of the holder in position to overlie the adjacent cutting edge of the blade, from which they curve away in the usual manner. These guard teeth also may be formed integral with the holder, and in case a double-edged blade is employed said teeth will ordinarily be provided at each side of the head or blade end of said holder, in which case the two halves of the holder may be made exactly alike and given a symmetrical contour. The diagonally-bent lugs 5 will evidently act not only to hold the blade against the guard teeth but also as stops to determine the proper adjustment of the cutting edge or edges of the razor with respect to said guard teeth, by preventing any movement of the blade either laterally or in an endwise direction.

In order to hold the blade firmly in place, means are provided for causing the two halves of the holder to approach each other

with some degree of force, and this may be done in a very simple manner by merely tempering the handle end of the holder to a sufficient extent to give it a spring action, the 5 spring pressure being operative in such direction and to such an extent as to cause the holding devices for the blade to move toward each other, when permitted to do so, until they are separated by a distance less than 10 the width of the blade. This is the construction illustrated in Figs. 2 and 3, and in this case the blade is released by merely forcing the two portions of the holder away from each other until the blade is free from 15 the retaining lugs 5, and is inserted in a similar manner.

Inasmuch as the function of the spring action in the holder shown in Fig. 2 is to hold the retaining lugs firmly in engagement 20 with the blade, it will be evident that this spring action may be replaced by other means for accomplishing the same result, in which case the bend at the end of the handle will merely need to be flexible, so as to serve 25 as a hinge. Thus in Fig. 4, I have shown the two halves 8—8 of the handle proper as flat and as receding slightly from each other as they approach the head of the razor, said handle being surrounded by a sleeve 9 adapt- 30 ed to slide lengthwise thereon and the arrangement being such that as said sleeve is slid toward the head of the device the two parts of the holder will be made to approach each other to a sufficient extent to grasp the 35 blade as above described.

In Figs. 6 and 7 a similar arrangement is shown in which the sleeve 9 is replaced by a pin 10 having heads 11 at its ends and arranged to slide in aligned longitudinally-ext- 40 tending slots 12 formed in the two portions of the handle, the desired closing pressure being applied to said portions of the handle by the heads of the pin 10 as the latter is moved away from the outer end of the han- 45 dle. In this construction, as well as in that shown in Fig. 4, it will be convenient to provide for a spring action at the free end of the handle which will tend to separate the two halves of the head, so that 50 when the sleeve 9 or headed pin 10, as the case may be, is moved outward on the handle, the two halves of the handle will automatically separate.

In Fig. 5 I have shown a handle 13 in 55 which the spring action at its free end tends to close the two halves of the head upon the blade, one portion of this handle being provided with a threaded perforation in which is located a thumb screw 14 adapted 60 to bear upon the opposite portion of the handle, so that by turning said screw the two portions of the handle may be positively separated and held apart to facilitate the removal or insertion of a blade.

The blade of my razor may have but one 65 cutting edge, if preferred, and in such case the guard teeth on one portion of the head of the razor may be omitted. Such a construction is shown in Fig. 8, in which a razor blade of the ordinary concave type 70 is shown at 15, that side of the holder 16 which grasps the rear or thick edge of the blade being provided with one or more lugs 17 having a sufficiently increased length to accommodate the greater thickness of the 75 blade at this edge. It will be evident that a blade having two cutting edges could be used with a holder having guard teeth on but one of its halves only, in which case it would be necessary to reverse the blade in 80 order to utilize both of its cutting edges.

It will be seen that in each of the constructions illustrated the ends of the blade are freely exposed in convenient position to be grasped by the user when inserting or 85 removing the blade, and that after the blade has been removed the holder may be cleaned with the utmost facility. It is to be understood however, that my invention is not limited to these specific constructions, or 90 any of them.

I claim as my invention:

1. In a safety razor the combination of a rectangular blade having two cutting edges and suitable end portions, a rectangular 95 holder having a pair of upwardly projecting lugs for each end of the blade, the members of each pair of lugs being separated or spaced apart to receive and embrace an end portion of the blade between them, to prevent displacement of the blade in all directions in the plane thereof, said upstanding lugs being disposed substantially at the four corners of the holder and blade, a guard for the cutting edge in use, a handle on the 105 bottom of the holder, and means bearing upon the upper surface of the blade to hold it fixed from displacement upon the holder.

2. In a safety razor the combination of 110 a rectangular blade having two cutting edges and suitable end portions providing additional transverse and longitudinal edges, a holder for the blade comprising a handle, a blade seat upon said handle, a pair of up- 115 standing lugs at each end of the blade seat engaging the said transverse and longitudi- nal edges of the blade, a guard for the cutting edge or edges, and means bearing upon the upper surface of the blade to hold it 120 fixed from displacement upon the holder.

3. In a safety razor, a holder for a double edged blade comprising a handle having two sides, the two sides being resilient and joined together at one end, and a frame 125 having two sides, the inner edges of said sides being joined each to a free end of the handle, the outer edges opposite and parallel

- to the said inner edges having each a row of teeth for seating the edges of the blade thereon, lips formed on the corners for gripping the blade, the distance between 5 adjacent lips on opposite sides of the frame when the blade is removed therefrom being of different dimension than the width of the blade, and means operating the handle for adjusting the frame to bring the lips in 10 spring pressed engagement with the blade.
4. In a safety razor, a holder for a double-edged blade comprising a handle having two sides, the two sides being resilient, and joined together at one end, a frame having 15 two sides, the inner edges of said sides being joined each to a free end of the handle, the outer edges opposite and parallel to the said inner edges having each a row of teeth for seating the edges of the blade thereon, 20 lips formed on the corners for gripping the blade, and a slide ring mounted on the handle adapted to be pushed up the handle to close the parts to bring the lips in spring pressed engagement with the blade.
5. In a safety razor, a holder for a double-edged blade comprising a handle having two sides, the two sides being resilient, and joined together at one end, a frame having 25 two sides, the inner edges of said sides being joined each to a free end of the handle, the outer edges opposite and parallel to the said inner edges having each a row of teeth for seating the edges of the blade thereon, and lips formed on the corners for gripping 30 the blade.
6. In a safety razor, a holder for a double-edged blade comprising a handle having two sides, the two sides being resilient and joined together at one end, and a frame 35 having two sides, the inner edges of said sides being joined each to a free end of the handle, the outer edges opposite and parallel to the said inner edges having each a row of teeth for seating the edges of the blade thereon, and lips formed on the corners for gripping 40 the blade.
7. In a safety razor, a holder for a double-edged blade comprising a handle, a frame having two sides connected to the handle and resiliently mounted relative to each other, the outer edge of each of the 45 sides having each a row of teeth forming a guard, and lips formed on the corners of the sides for gripping the blade.
8. In a razor, a blade having oppositely disposed cutting edges, a frame member provided with guard portions, and means for securing the blade in place with its cutting edges adjacent the guard portions, said securing means comprising oppositely disposed devices arranged to engage the blade 50 at opposite separated points to leave the cutting edges unobstructed and adapted to re- 55 cede from and release the blade upon their separation.
9. In a razor, the combination of a frame member having a guard portion, a blade, 70 means on the frame member for engaging the blade at its corner portions only to clamp the blade with its edge in proximity to the guard portion, two of said blades engaging means being located at opposite ends of the 75 guard portion and being movable relative to other said blade supporting means in a path parallel with the plane of the blade to clamp and release the blade.
10. In a razor, the combination of a frame 80 member provided with a guard portion, a blade, means carried by the frame member and arranged to engage the blade at its corner portions only, some of said means being movable in a path parallel with the plane 85 of the blade to removably secure the blade with its cutting edge in proximity to the guard portion.
11. In a razor, the combination with a blade of rectangular formation provided with two 90 parallel cutting edges, of a frame comprising two members movable one relative to the other, there being an elastically yieldable connection between such members, each of the members being provided with a portion constituting 95 a guard for one of the cutting edges of the blade, engaging members carried by each of the frame members and located in position for engaging the corners of the blade at the ends of the cutting edges, for 100 holding the blade in proper position relative to the guard.
12. In a razor, the combination with a blade having two parallel cutting edges and transversely disposed ends, of a frame comprising two members movable one in respect of the other, each of said frame members being provided with a blade supporting guard for one of the cutting edges of the blade, a pair of engaging members carried 105 by each of the frame members and each located in position for engaging one corner of the blade for holding this in proper position relative to the supporting guard of such frame member.
13. In a razor, the combination with a blade of rectangular formation, of a frame comprising two members movable one relative to the other, one of the members being provided with a portion constituting a guard 115 for the cutting edge of the blade, positioning members carried by the frame and located in position for engaging the corners of the blade for holding this in proper position relative to the guard, said positioning members lying partially in the path of endwise movement of the blade to obstruct said endwise movement, some of said positioning members being carried by one of said frame members and some of said positioning 120 members being carried by the other of said frame members.
14. In a razor, the combination with a blade of rectangular formation, of a frame comprising two members movable one relative to the other, one of the members being provided with a portion constituting a guard 125 for the cutting edge of the blade, positioning members carried by the frame and located in position for engaging the corners of the blade for holding this in proper position relative to the guard, said positioning members lying partially in the path of endwise movement of the blade to obstruct said endwise movement, some of said positioning members being carried by one of said frame members and some of said positioning 130 members being carried by the other of said frame members.

members being carried by the other of said frame members for releasably holding the blade in the frame and adjacent the guard.

14. In a razor, the combination with a frame, having means for supporting the cutting edge of a rectangular blade and means for supporting the rear edge thereof, and positioning members carried by the frame and located in position, one for engaging each corner of the razor blade and said positioning members lying partially in the path of endwise movement of the blade to obstruct said endwise movement, and means for moving two of said corner engaging members toward the other two for preventing edgewise movement of the blade, either longitudinally or laterally.

15. In a safety razor the combination with a pair of frame members one movable toward and from the other, each being provided with a suitable bearing surface, and a pair of blade engaging members mounted on each frame member adjacent the bearing surface and each disposed at an angle of about forty-five degrees to the path of frame-member movement to lie partially in the path of endwise movement of the blade to obstruct said endwise movement, the inward faces of diagonally opposite blade engaging members being disposed on substantially parallel planes.

16. In a safety razor the combination with a pair of frame members one movable toward and from the other, each being provided with a suitable bearing surface, and a pair of blade engaging members mounted on each frame member adjacent the bearing surface and each disposed at an angle of about forty-five degrees to the path of frame-member movement, the inward faces of diagonally opposite blade engaging members being disposed on substantially parallel planes, said engaging members being provided with portions for overlying the outer surface of the blade.

17. In a razor, the combination with a blade having two parallel cutting edges and transversely disposed ends, of a frame comprising two members movable one in respect of the other, each of the frame members being provided with a suitable bearing surface, and one of the frame members being provided with a portion adjacent to the bearing surface constituting a guard for one of the cutting edges of the blade, a pair of engaging members carried by each of the frame members and each located in position for engaging one corner of the blade for holding this in proper position relative to the bearing surface and guard of such frame member, said engaging members lying partially in the path of endwise movement of the blade to obstruct said endwise movement.

18. In a safety razor the combination with a blade having two parallel cutting edges,

transversely disposed ends and frustrated corners uniting the edges and the ends, of an engaging member for each said corner, and means for elastically pressing two of said engaging members toward the other two of 70 said engaging members, said engaging members lying partially in the path of endwise movement of the blade to obstruct said endwise movement.

19. In a safety razor, a frame comprising 75 portions constituting a pair of guards for the cutting edges of a double-edged blade, and supporting means for supporting a blade in proper position relative to said guards and comprising off-set members 80 formed with means located in position to engage the blade at points adjacent to and beyond the cutting edges thereof for securing the same in place relative to the guards.

20. In a safety razor the combination of a frame comprising two parts and elastic means connecting these, each of said parts having a portion constituting a guard for the cutting edge of a blade and blade clamping means, overlying the outer face of the 90 blade, the blade clamping means on each part being co-operative with the blade clamping means on the other part.

21. In a safety razor, the combination with a pair of guards one for each edge of a 95 double edged blade, each guard having a bearing surface for engaging the blade inwardly of each guard, and engaging members engaging the blade at each corner and located in position to expose both cutting 100 edges and both ends.

22. In a safety razor the combination with a razor blade having a pair of substantially parallel edges one of such edges being a cutting edge, and a pair of transversely disposed edges, of a support for engaging flat face of the blade inwardly of its cutting edge, a guard for the said cutting edge of the blade associated with said support, a positioning member located at each 110 end of the guard, each positioning member being located in position to resist outward longitudinal or transverse movement of the corner of the blade engaged thereby, a support for the face of the blade at its edge opposite its cutting edge, and a positioning member located at each end of said support, each positioning member being located in position to resist outward longitudinal or transverse movement of the corner of the 120 blade engaged thereby.

23. In a safety razor the combination with a razor blade having a pair of substantially parallel edges one of such edges being a cutting edge, and a pair of transversely disposed edges, of a guard for the cutting edge of the blade, a positioning member located at each end of the guard, means for supporting the other edge of the blade, an elastically yieldable connection between the 130

guard and support and a positioning member located at each end of the guard and at each end of the support each of said members being located in position to resist
5 movement of the corner of the blade engaged thereby in a longitudinal or in a transverse direction.

In testimony whereof, I have hereunto subscribed my name this twentieth day of February, 1905.

KING C. GILLETTE.
